TAPE SUPPORTING RACK

Charles D. Oakes and Mack D. Harris, High Point, N.C., assignors to MacPanel Company, High Point, N.C., a corporation of North Carolina

Filed Nov. 1, 1960, Ser. No. 62,692

Term of patent 14 years

(Cl. D33—3)

The dot-dash line indications of a tape are for illustrative purposes only.

We claim:

The ornamental design for a tape supporting rack, as shown and described.
